UNITED STATES PATENT OFFICE

2,501,603

QUICK RELEASE DETENT PAWL

Arthur Clifford Howard, Upminster, England,
assignor of one-half to Rotary Hoes Limited,
East Horndon, England

Application February 20, 1948, Serial No. 9,727
In Great Britain June 28, 1944

Section 1, Public Law 690, August 8, 1946
Patent expires June 28, 1964

8 Claims. (Cl. 254—108)

1

This invention relates to single and double-acting lifting jacks of the pawl and rack operated type, whether reversible or otherwise.

These jacks, when single-acting, have an actuating pawl whereby the rack is raised step-by-step, and a detent pawl to hold the rack whilst the actuating pawl is moved in preparation for each lifting operation. When these jacks are double-acting, the actuating and detent pawls are each adapted alternately to raise the rack and hold it. When the jacks are reversible, they can also be lowered step-by-step.

Lifting jacks of the type referred to have heretofore been provided with means for withdrawing the pawls from the loaded rack so as to drop the object that had been lifted. In withdrawing the pawls, however, a progressively diminishing cross-section of the rack teeth is constrained to withstand the full load, until disengagement is completed, with the result that the tips of the rack teeth, and in some instances the pawls, have been damaged. Jacks that have sustained damage of this nature are rendered unreliable in action, due to faulty engagement of the pawls with the damaged rack teeth, and instances are known where loads have inadvertently been dropped during normal lifting with resultant injury to personnel and damage to the object being lifted.

My object is to provide a jack, of the type set forth, with means for permitting the lifting table to be lowered suddenly, while under load, without injury to the teeth of the rack or to the pawls.

According to the present invention, a jack of the type set forth is provided with support means for the detent pawl, which support means can, when it is desired to drop the load and the actuating pawl is withdrawn from the rack, be moved to un-support the detent pawl and permit the latter to be urged freely out of engagement with the rack by the descent of the latter due to the load.

An embodiment of the invention, as applied to a single-acting jack, will now be described with reference to the accompanying drawings, in which:

Figure 1 is a side elevation, partly in section, showing the various parts in the positions they occupy at the completion of a lifting operation;

Figure 2 is a fragmentary side elevation showing the lifting pawl retracted to permit the withdrawal of the detent pawl; and

Figure 3, which is a view similar to Figure 2,

2

shows how the detent pawl is disengaged from the rack, so as to drop the load, without the development of any harmful pressure during such disengagement.

5 The jack shown comprises a body 11, a rack 12 with a load-supporting table 13 or 13a, a lifting pawl 14, and a detent pawl 15.

The lifting pawl 14, as shown, is constructed and supported, as described in British Patent 10 No. 577,639, it being spring-loaded, as necessary or desired, in any suitable manner. This comprises pivotally securing the foot of the pawl, by a strap 16, to a bearing barrel 17 extending between the two side walls of a hollow operating lever 18 which latter is supported by external trunnions 19 in the jack body; the arrangement permitting the barrel 17 and trunnions 19 to overlap for securing a high mechanical advantage and the barrel 17 providing a large bearing surface for the pawl so as to secure a low intensity of loading. A tommy bar, not shown, is inserted in the lever 18 for operating the jack.

15 The detent pawl 15 is housed in a guide 20 which locates it laterally and permits it to move obliquely into and out of engagement with the rack. The foot of the detent pawl is pivoted at 21 in a cylindrical recess at the top of a link 22 having its lower end similarly pivoted to the arm 23 of a bell-crank lever 24 that is itself

20 pivoted at 25 to the body 11; a spring-loaded hook member 21a holding the pawl and link in position, and the bottom of the guide 20 forming a cross-head for the pivot 21. It will be seen that the link 22 and arm 23 form a toggle. The other arm 26 of the bell-crank lever is substantially U-shaped in cross-section and forms the bottom of a housing for the reception of a tommy bar 27. The top of this housing is constituted by the foot 28 of a slide 29 supported in a guide 30 formed in the body 11; the top of the slide projecting through the guide at 31 just beneath the operating lever 18.

25 During normal operation of the jack, that is, with the parts as shown in Figure 1, the foot of the slide rests upon an arcuate portion 32 of one side wall 33 of the U-section arms 26 of the bell-crank lever and engages behind an abutment 34 formed in the wall 33. The slide thus holds the bell-crank lever 26 with its pivot to the link 22 in an over-centre position to the left of Figure 1 and with the inner end abutting the guide 20 at 35. The thrust on the detent pawl is therefore supported by the pivot 25 of the bell-crank lever and at the abutting point 35. In this position the operating lever 18 prevents the slide

29 from being moved for disengaging its foot from the abutment 34, so that there is no fear of the support for the detent pawl being accidentally withdrawn.

When it is desired to drop the load, the operating lever 18 is raised to the position shown in Figure 2, thus lowering the pawl 14, which latter, due to the co-action of its oblique surface 39 with the cross-bar 36 (which is fast with the body 11), becomes disengaged from the rack; the load then being supported by the detent pawl. This movement of the lever 18 removes its obstruction to the upward movement of the slide 29 so that, when the tommy bar 27 is inserted in the arm 26 of the bell-crank lever to abut a stop 37, in which position it engages the underside of the foot 28 of the slide, the slide can be raised to free the abutment 34. That is to say, depression of the free end of the tommy bar 27 causes the tommy bar to rock about the free end of the arm 26 as a fulcrum, see Figure 3, and it is during the first part of this movement that the slide 29 is raised against the pressure of its return spring 38, in order for its foot 28 to clear the abutment 34. As soon as the abutment 34 has been cleared in this way the reaction of the tommy bar on the free end of the arm 26 causes the bell-crank lever 24 to turn clockwise with a snap action until its pivotal connection to the link 22 passes over-centre with respect to the pivots 21 and 25 so as to un-support the detent pawl 15. The rack then descends under the load and traverses the detent along the guide 20; the inclination of the latter to the line of movement of the rack, and the spring-loading of the hook member 21a, disengaging the pawl from the rack. It will thus be seen that, due to the detent pawl being un-supported during disengagement there is negligible pressure between it and the rack teeth while the load is being dropped.

Also, as soon as the tommy bar has moved the bell-crank over the dead-centre position, during the disengagement of the detent pawl, the spring hook 21a asserts itself and enhances the snap action referred to above.

It will be obvious that, in the case of a double-acting jack, the detent pawl can be supported in a manner similar to that above described. Also, that the detent pawls of reversible jacks, whether single or double-acting may be similarly supported.

What I claim as my invention and desire to secure by Letters Patent of the United States is:

1. A lifting jack comprising a body, a ratchet-toothed rack fast with a table for supporting a load and axially-slidably supported in said body, an operating lever pivoted to said body, a lifting pawl for coaction with said rack pivoted to said operating lever, a detent pawl for coacting with said rack, a guide for said detent pawl fast with said body and diverging from the axis of said rack, and movable means which in one extreme position supports said detent pawl for supporting said rack and which in another position, when said lifting pawl is withdrawn from engagement with said rack, unsupports said detent pawl so that the latter, due to the inclination of its said guide, is urged out of engagement with said rack due to the descent of the latter under the influence of gravity.

2. A lifting jack comprising a body, a ratchet-toothed rack fast with a table for supporting a load and axially-slidably supported in said body, an operating lever pivoted to said body, a lifting

pawl for coaction with said rack pivoted to said operating lever, a detent pawl for coaction with said rack, a guide for said detent pawl fast with said body and diverging from the axis of said

5 rack, movable means which in one extreme position supports said detent pawl for supporting said rack and which in another position, when said lifting pawl is withdrawn from engagement with said rack, unsupports said detent pawl so that the latter, due to the inclination of its said guide, is urged out of engagement with said rack due to the descent of the latter under the influence of gravity, and a locking-means for holding said movable means in the detent-pawl-supporting position, said operating lever obstructing the disengagement of said locking-means from said movable means except when said operating lever has been moved for completely withdrawing said lifting pawl from engagement with said rack.

20 3. A lifting jack comprising a body, a ratchet-toothed rack fast with a load-supporting table and axially-slidably supported in said body, an operating lever pivoted to said body, a lifting pawl for coaction with said rack pivoted to said operating lever, a toggle-means pivoted to said body, a detent pawl for coaction with said rack pivotally supportable by said toggle-means, locking-means for holding said toggle-means in an angular position for supporting said detent pawl

25 30 for coaction with said rack, said operating lever obstructing the withdrawal of said locking-means from the locking position except when said operating lever is swung to a non-operative position, a lever fast with said toggle means for coaction

35 40 with a tommy bar for turning said toggle means, when unlocked, into an angular position in which it unsupports said detent pawl, said tommy bar reacting on said locking-means to move the latter from its locking position, and an inclined guide for said detent pawl for withdrawing it, when unsupported, from engagement with said rack by the descent of the latter under gravity.

4. A lifting jack comprising a body, a ratchet-toothed rack fast with a load-supporting table and axially-slidably supported in said body, an operating lever pivoted to said body, a lifting pawl for coaction with said rack pivoted to said operating lever, toggle-means pivoted to said body, a detent pawl for coaction with said rack pivotally supportable by said toggle-means, a stop for holding said toggle-means in one over-centre position for supporting said detent pawl for coaction with said rack, locking-means for locking said toggle-means in said one over-centre position, said operating lever obstructing the withdrawal of said locking-means from the locking position except when said operating lever is swung to a non-operative position, a lever fast with said toggle means for coaction with a tommy bar for turning said toggle means, when unlocked, into an opposite over-centre position in which it unsupports said detent pawl, said tommy bar reacting on said locking means to move the latter from its locking position, and a guide for said

55 60 70 detent pawl extending obliquely-downwardly from the path of the rack, said guide being for withdrawing said detent pawl, when the latter is unsupported, from engagement with said rack by the descent of the latter under gravity.

5. A lifting jack comprising a body, a ratchet-toothed rack fast with a load-supporting table and axially-slidably supported in said body, an operating lever pivoted to said body, a lifting pawl for coaction with said rack pivoted to said operating lever, a bell crank lever pivoted to

said body, a detent pawl, an inclined guide for said detent pawl for guiding it from engagement, when unsupported, with said rack by the descent of the latter under gravity, a link connecting one arm of said bell-crank lever to the foot of said detent pawl, an abutment fast with said body for holding said bell-crank lever with said link in one over-centre position for supporting said detent pawl for coaction with said rack, an abutment formed on said bell-crank lever, and a slide 10 guided by said body and for coaction with said abutment on said bell-crank lever for locking said bell-crank lever in the detent-pawl-supporting position, said operating lever obstructing the withdrawal of said slide from the locking position except when said operating lever is swung to a non-operative position in which said lifting pawl is disengaged from said rack, the other arm of said bell-crank lever being for coaction with a tommy bar for turning said bell-crank lever, when unlocked, to bring the connection between said link and said one arm of said bell-crank lever into an opposite over-centre position in which said detent pawl is unsupported, said tommy bar reacting on said slide to move the latter from its locking position.

6. A lifting jack, according to claim 5, of which the said other arm of said bell-crank lever is of channel section to form a lower housing part for said tommy bar, and the adjacent end of said slide forms an upper housing part for said tommy bar, the movement of said slide, when unlocked, from its locking position being effected by pivoting the tommy bar about the outer end of said lower housing part and the consequent pressure of said tommy bar on said outer end

enabling said bell-crank lever being moved, with a snap action, for unsupporting said detent pawl.

7. A lifting jack, according to claim 5, comprising a spring for biassing said slide into its locking position.

8. A lifting jack comprising a body, a ratchet-toothed rack fast with a table for supporting a load and axially-slidably supported in said body, an operating lever pivoted to said body, a lifting pawl for coaction with said rack pivoted to said operating lever, a detent pawl for coaction with said rack, a guide for said detent pawl fast with said body and diverging from the axis of said rack, movable means which in one extreme position supports said detent pawl for supporting said rack and which in another position, when said lifting pawl is withdrawn from engagement with said rack, unsupports said detent pawl so that the latter, due to the inclination of its said guide, is urged out of engagement with said rack due to the descent of the latter under the influence of gravity, and spring means acting on said detent pawl to assist in such disengagement of said detent pawl and rack.

ARTHUR CLIFFORD HOWARD.
